Inventor,

UNITED STATES PATENT OFFICE.

EARLE A. BERRY, OF KANSAS CITY, MISSOURI.

CONCRETE-MOLD.

1,162,554.

Specification of Letters Patent.

Patented Nov. 30, 1915.

Application filed January 10, 1914. Serial No. 811,482.

To all whom it may concern:

Be it known that I, EARLE A. BERRY, a citizen of the United States, residing at Kansas City, in the county of Jackson and State of Missouri, have invented new and useful Improvements in Concrete-Molds, of which the following is a specification.

The invention relates to molds for concrete construction.

10 The primary object of the invention is the provision of a mold wherein the walls of a building, silo or the like can be erected in a novel manner to assure strength and durability thereto and also to enable the convenient and quick building thereof from concrete or cementitious material.

Another object of the invention is the provision of a mold wherein the sections thereof can be readily positioned for the formation 20 of the walls of the building and also which will hold the metal lathing in permanent position for the application of plaster to give a finish to the facing of the inner or outer wall.

25 A further object of the invention is the provision of a mold wherein the desired air space between the inner and outer walls can be had and the thickness of such walls varied as the occasion may require.

30 A still further object of the invention is the provision of a mold wherein the mold sections can be readily and easily assembled and disassembled.

A still further object of the invention is 35 the provision of a mold wherein the reinforcing bars can be held for the proper placing of the same in the wall when being formed with the mold.

40 A still further object of the invention is the provision of a mold by which circular walls of different diameters may be constructed by the use of a greater or smaller number of the plate sections.

45 A still further object of the invention is the provision of a mold which is simple in construction, reliable and efficient in operation, and inexpensive in manufacture.

With these and other objects in view, the invention consists in the construction, combination and arrangement of parts as will be hereinafter fully described, illustrated in the accompanying drawings, and pointed out in the claims hereunto appended.

50 In the drawings:—Figure 1 is a fragmentary horizontal sectional view through a wall showing the mold in position for erect-

ing the same. Fig. 2 is a vertical transverse sectional view through the wall, showing the metal lathing in position and also the mold for the erection of inner and outer spaced walls. Fig. 3 is a similar view, showing the spacer cones in position relative to the metal lathing and the facing plaster applied thereto. Fig. 4 is a perspective view of the mold. Fig. 5 is a vertical longitudinal sectional view therethrough. Fig. 6 is a fragmentary plan view looking toward the outer face of a wall when the molds are in stacked position. Fig. 7 is a sectional view on the line 7—7 of Fig. 6.

70 Similar reference characters indicate corresponding parts throughout the several views in the drawings.

Referring to the drawings in detail, A designates the outer wall of the building 75 which is made from concrete and constructed by the use of the mold hereinafter fully described.

The mold comprises a pair of spaced rods 10 having threaded ends 11 and plate sections 12 and 13 which are provided with holes 14 for receiving the rods 10, while adjustably engaged on the ends 11 of the rods 10 are inner and outer lock nuts 15 which are adapted to work against washers 16 positioned between the nuts 15 and the faces adjacent thereto of the plate sections 12 for fastening the same on the rods, it being understood of course that the rods can be made of any desirable length, thereby enabling 90 the thickness of the walls of the building to be varied. The rods 10 are bent to form alining eyes 17 through which is passed a reinforcing rod 18 which is held seated in the eyes and is designed to be embedded in the 95 outer wall A for strengthening the same. The rods 10 for a portion of their length are flattened at 19 and at which points are provided openings 20 in which are detachably engaged cotter pins 21 to hold the plate section 13 in proper position when building the wall A, in a manner presently described.

In erecting the wall A one plate section 12 is secured at the ends of the rods 10 and securely fastened thereto by the nuts 15 at 105 opposite sides of the same. Also the plate section 13 is positioned on the rods 10 to engage against the cotter pins 21. After the adjustment of the plate sections on the rods 10 the same are brought to rest upon a 110 foundation, and thereafter the concrete is poured while wet between the plate sections

so that the rods 10 will be positioned transversely therethrough, it being understood of course that the reinforcing rod 18 is engaged in the eyes 17 so as to become embedded in the concrete when poured between the plate sections. The mold now remains in such position until the concrete becomes hardened, and thereafter the plates 12 and 13 are removed from the rods which are 5 10 permanently held in the section of the wall thus formed.

Should it be desired to erect an inner wall and an air space between it and the outer wall A, the cotter pins 21 are adjusted in the 15 rods 10, and thereafter the metal lathing B is engaged on the latter against the said pins, and finally one of the plates 12 is fastened on the ends of the rods 10 by the nuts 15, and the concrete or plastic material is 20 poured between the metal lathing and the plate for the formation of the inner wall C, as shown in Fig. 2 of the drawing. Thus it will be seen that an air space D is provided between the walls A and C. It is of course 25 to be understood that the plate sections 12 and 13 are of the required length for the formation of the sections of the wall during repeated operations in the use of the mold. Now, should it be desired to construct a 30 plastic surface to the metal lathing E as shown in Fig. 3 of the drawings, the rods 10, which are permanently mounted in the wall A, have fitted over their ends projected beyond the inner faces of the said wall A 35 cone members 22 which are filled with cement or other like material as at 23, and thereafter the metal lathing 24 is hung upon the ends of the rods 10, the cone members 22 being designed to serve as spacing elements 40 for the metal lathing to hold the same a distance from the wall A. The metal lathing 24 is held on the rods by means of the nuts 15, which are threaded thereon as shown in Fig. 3 of the drawing. After the lathing 24 45 is properly positioned, the plastic material E is applied thereto.

To enable the stacking of several of the molds, there is provided on the plate sections 12 and 13 contiguous to their lower

edges cleats 25 which permit the fastening 50 of the plate sections together when one mold is arranged above the other for the formation of the wall of a building.

From the foregoing it is thought that the construction and manner of use of the mold 55 will be clearly understood, and therefore a more extended explanation has been omitted.

What is claimed is:—

1. A mold comprising a plurality of 60 spaced rods, eyes formed in the rods adjacent one end thereof, a reinforcing bar passed through said eyes, molding sections detachably and adjustably mounted upon the ends of said rods, each of said rods having a flattened intermediate portion disposed at a right angle to the eye thereof and provided with openings, and pins engaged in said openings for spacing intermediate molding sections relative to each other. 70

2. A mold comprising a plurality of spaced rods, hollow cone-shaped members encircling said rod and spaced therefrom, and adapted to hold a cementitious filling, said cones being closed at one end by said support, molding sections mounted on the ends of said rods, a metal lathing mounted upon the free ends of said rods and closing the opposite ends of said cones, said cones spacing the lathing relative to the said support, and means for securing the lathing upon said rod. 80

3. As a new article of manufacture, a tie rod adapted to space mold plates formed to provide an eye adjacent one end thereof and a flattened intermediate portion disposed at a right angle with relation to said eye and provided with openings, pins removably positioned in said openings, said rod having threaded terminals, and nuts adjustably associated therewith. 90

In testimony whereof I affix my signature in presence of two witnesses.

EARLE A. BERRY.
